(57) CLAIM

The ornamental design for a garment, as shown and described.

DESCRIPTION

FIG. 1 is a front view of a garment according to the design; FIG. 2 is a rear view thereof; FIG. 3 is a left side view thereof; FIG. 4 is a right side view thereof; FIG. 5 is a front perspective view thereof; FIG. 6 is a rear perspective view thereof; FIG. 7 is a front view thereof shown in an environment of use; FIG. 8 is a rear view thereof shown in an environment of use; and, FIG. 9 is a left side view thereof shown in an environment of use, the right side view being a mirror image thereof. The portions of the garment shown in broken lines in FIGS. 1-9 do not form part of the claimed design. The broken line showing of the feet, arms, and torso in FIGS. 7-9 is for the purpose of illustrating portions of the environmental structure and forms no part of the claimed design. The claimed design includes all surfaces that are shown with shade lines and extends to but does not include the adjacent broken lines.
